Specification of Letters Patent. Patented Aug. 29, 1916.

Original applications filed August 11, 1910, Serial No. 576,758, and August 7, 1911, Serial No. 642,685.
Divided and this application filed January 2, 1915. Serial No. 305.

To all whom it may concern:

Be it known that we, FRANK M. PIERCE and WILLIAM B. PIERCE, citizens of the United States, and residents of the city of Chicago, in the county of Cook and State of Illinois, have invented certain new and useful Improvements in Shuttles; and we do hereby declare that the following is a full, clear, and exact description of the same, reference being had to the accompanying drawings, and to the numerals of reference marked thereon, which form a part of this specification.

This invention relates to a hollow shuttle adapted to carry folds of papers, and constitutes a division of our copending applications for patent for "wrapping machines", filed August 11, 1910, Serial No. 576,758, and "wrapping machines", filed August 7, 1911, Serial No. 642,685. In this particular type of shuttle the wrapping paper is laid in arc shaped folds within the shuttle, and the strip is drawn through a small opening provided in the inner wall of the shuttle across to the opposite side of the shuttle and thence through a tension device and folding mechanism, and is finally led to the article being wrapped.

It is an object therefore of this invention to construct a sectional shuttle having a chamber therein adapted to carry folded wrapping material, and provided with tension and folding devices for the wrapping material to insure proper application thereof to an article being wrapped.

It is also an object of this invention to construct a sectional shuttle the sections of which are hingedly connected to permit the shuttle to be opened for insertion of an article to be wrapped thereinto, and with spring latching means to lock the sections when the same are moved into closed position, and with the wrapping material laid in arc shaped folds concealed within said shuttle.

It is furthermore an important object of this invention to construct an annular hollow sectional shuttle to permit the same to be opened to permit insertion of an article to be wrapped thereinto, after which the sections are swung into closed position, auto-

matically locking therein, and with hinged walls which may be opened to permit insertion of wrapping material into the shuttle.

It is finally an object of this invention to construct a shuttle adapted to carry wrapping material and to be used in a power driven wrapping machine, resting between suitable guide disks and driven by a gear meshing with a gear forming a part of said shuttle.

The invention (in a preferred form) is illustrated in the drawings and hereinafter more fully described.

In the drawings: Figure 1 is a side elevation of a wrapping machine with which a shuttle embodying the principles of our invention is used. Fig. 2 is a top plan view thereof. Fig. 3 is a reduced rear elevation of a shuttle. Fig. 4 is a slightly larger sectional view taken therethrough, showing parts in elevation. Fig. 5 is a top plan view of the shuttle. Fig. 6 is an enlarged detail view of the latch for closing the outer wall of the shuttle. Fig. 7 is a view taken on line 7-7 of Fig. 5. Fig. 8 is a view in elevation taken in the direction of the arrows on line 8-8 in Fig. 4. Fig. 9 is an enlarged sectional detail taken on line 9-9 of Fig. 4. Fig. 10 is a transverse section of the shuttle 80 showing the tension adjusting mechanism in elevation. Fig. 11 is an enlarged elevation taken on line 11-11 of Fig. 4, showing the opposite side of the folding device from that shown in Fig. 9. Fig. 12 is a front end elevation thereof. Fig. 13 is a section taken on line 13-13 of Fig. 10, taken longitudinally of the tension adjusting mechanism and showing the adjusting bolt and web member in elevation. Fig. 14 is a section 90 taken on line 14-14 of Fig. 13. Fig. 15 is a view similar to Fig. 4 of another form of shuttle. Fig. 16 is a section on line 16-16 of Fig. 15.

As shown in the drawings, the shuttle 95 hereinafter described is shown associated with a tire wrapping machine of which only a side and top view is herein illustrated, these being sufficient to show the position and relation of the shuttle thereto. The 100 machine briefly described consists of upright frame members 1 and 2, and mounted

in the frame of the machine adjacent said side members are vertical cylindrical guide bars 3, having slidably supported thereon a carriage 4. Said carriage is provided near the rear end thereof on each side with outwardly extending upper and lower brackets having secured thereon sleeves 5, in vertical alinement adapted to engage around said guide rods 3.

10 Journaled horizontally at the front and rear of the carriage between the side members thereof are friction rollers 6 and 7, respectively, of relatively large size, the surface of which may be milled or slightly 15 roughened or covered with any suitable investing material to assist in frictionally driving the article to be wrapped when supported thereon. The shafts for said frictional rollers or wheels 6 and 7, are extended beyond the side frame members of the carriage on one side thereof, and are provided each with sprocket wheels 8, to receive a sprocket chain 9, about the same whereby said rollers are driven simultaneously and at equal rates in the same direction.

10 A driving shaft 10, is journaled on the front and rear portions of the frame, and is provided with a driving pulley 11, which is secured thereon by means of a suitable clutch, denoted as a whole by the reference 30 numeral 12. Said shaft is provided with a worm 13, near the rear side of the machine, which meshes with a worm gear 14, secured 35 on a vertical shaft 15, on which is feathered a bevel gear 16, which meshes with a bevel gear 17, secured on the end of the shaft for the friction pulleys before described, so that 40 said friction pulleys or wheels are driven continuously from the driving shaft independent of the vertical adjustment of the carriage. Also secured on said shaft 10, directly above the middle of the carriage before described, are parallel guide disks 18 45 and 19, which are of substantially equal diameter and of which, as shown, the rear disk comprises a plain inner supporting rim and an outer geared rim 20. Secured upon a shaft 21, on the opposite side of the machine and parallel to the shaft 10, are corresponding idler guide and supporting disks 22 and 23, respectively. Said four 50 disks support thereon and therebetween the annular revoluble shuttle wherein is carried 55 the wrapping material. Said shuttle comprises two segment members articulated together and affording therein a compartment to receive the wrapping material. Said shuttle consists of apertured side wall 60 members 24 and 25, articulated together at their meeting ends by means of a rivet 26, secured thereto to afford a pintle. Said side walls are connected transversely by means of webs or plates 27 and 28, respectively, 65 affording one end of the carton compart-

ments formed by the respective shuttle sections and also by means of transverse pins or rivets 29, on diametrically opposite sides thereof which hold the side walls of the shuttle spaced equal distances apart and 70 which also serve to secure thereto the lower half 30, of the sheet metal outer peripheral wall for the shuttle. As shown also, the meeting ends of the shuttle segments are provided with transverse end walls 31 and 32, respectively, which abut against each other when the shuttle is closed, and are provided with registering apertures through which extends a spring pressed bolt 33, secured in one of the shuttle sections. As 75 shown, approximately half the outer peripheral wall for the shuttle is hinged to open outwardly therefrom to permit the insertion of wrapping material X, in the folded half, as clearly shown in Fig. 4. For 80 this purpose a short leaf 34, is engaged in each of the pintles 29, and is connected by means of a pintle 35, with longer leaf sections 36 and 37, respectively. As clearly 85 shown in Figs. 4 and 7, the section 36, is provided with a tongue 38, adapted to pass through a corresponding slot in the outer end of the section plate 37, and to rest upon a transverse bar 39, secured across said slot on the inside of said plate at the extremity thereof. A bolt 40, is slidably engaged on the inner side of the plate 37, and at its outer end curves upwardly and outwardly to engage over the tongue 38, on the plate 36. As shown pulling springs 41, are secured on said bolt and on the rigidly mounted transverse bar 39, and act to hold said bolt forwardly or in engaging position, and finger apertures are provided through both of said plate sections 36 and 37, to permit the retraction of the bolt to release said plates the one from the other. Said shuttle is provided on its forward side wall with a peripheral rim or flange 42, which tracks upon and between guide disks 19 and 23, as clearly shown in Figs. 1 and 2, and on its rear side wall is provided with a corresponding flange or rim 43, to track on the corresponding portion 20, of the guide disk 18, and the guide disk 22, and a geared rim 44, is secured on the outer side of said rim 43, to mesh with the geared portion 20, of said guide disk 18, so that the shuttle thereby is continuously driven from the driving shaft 10. The respective shuttle sections are provided with the inner peripheral walls 45 and 46, respectively, as clearly 110 shown in Figs. 4 and 7.

Parallel guide rollers 47 and 48, respectively, are provided near the hinge in the inner peripheral wall 46, of the shuttle near the hinged end of the inner walls and between which the paper or other wrapping strip X, is fed outwardly. Mechanism is provided to prevent any portion of the 115 120 125 130

wrapping material folding when the shuttle is opened or closed, due to engagement between the hinged portions of the shuttle. For this purpose, as shown, a transverse bar or plate 49, is secured flush with the inner wall 46, and in close relation with said guide rolls and secured thereon is a spring plate or bridge member 50, which extends within the other shuttle section and bears on the inner wall 45, thereof, as clearly shown in Figs. 4 and 7, so that when the shuttle opens the package of wrapping material within the shuttle is supported thereon at the middle.

- 15 Within a compartment or space provided therefor on the end of the shuttle section from which the wrapping material is drawn, as shown in Fig. 4, is a tension device for the wrapping material and also a folding 20 mechanism for folding the wrapping strip longitudinally before wrapping the same about the body to be wrapped. Said tension device comprises a spring plate 51, secured transversely in the end of said shuttle 25 section and free near the outer periphery of said section. Pivotaly engaged upon a pintle 52, extending through the side walls of the section is a lever 53, the outer end (or that directed toward and bearing against 30 the free end of the spring 51) having a roller 54, journaled thereon. Secured on the inner end of said lever 53, is an angular sleeve 55, into which extends a wedge member 56, comprising a nut threaded on a 35 screw shaft 57, extending through the side walls of the section, and provided with a head at one end shaped to be engaged by a suitable tool to rotate said screw shaft to adjust the wedge inwardly or outwardly, 40 and thereby spring the end of the lever toward or from the spring plate 51. As shown, a leaf spring 58, is engaged at its end on said end of the lever, and tends at all times to hold the inner end of the lever outwardly 45 from the wedge, as shown in Fig. 13.

Pivotaly engaged in the end of the shuttle segment adjacent the roller 54, for the tension device, is the folder for the wrapping material. This comprises, as shown, a 50 plate 59, engaged at one end on a suitable pin or pintle 60, secured through the side walls of the shuttle section and curved outwardly from the roller 54, and directed inwardly toward the article to be wrapped. 55 Integrally connected therewith at one side thereof is a guide plate 61, of sufficient width at the entrance end thereof to receive the paper at its full width, and tapering toward its free extremity to afford a narrow restricted exit nozzle and turned at its free 60 edge over the plate to bend or fold the wrapping material thereover as it is drawn therethrough. Within a corresponding compartment in the other shuttle section a wire spool or bobbin 62, is journaled, and adja-

cent thereto is a tension roller 63, provided with a central groove thereon about which the wire may be turned one or more times to afford the requisite tension before being applied to the article to be wrapped. As shown, the hub 64, of the wire bobbin, is relatively large and is journaled upon a screw or bolt 65, which extends through said hub and is threaded into the side wall 75 of the shuttle section.

The bolt 33, whereby the shuttle sections are locked in closed position, is pivotally engaged on a suitable pintle 66, extending through the shuttle sections and is normally held in engaging position by means of a spring 67, which bears on the free end or tail thereof, as clearly shown in Fig. 4. A serrated cutter 68, is provided at the end of the shuttle sections adjacent the folder in convenient position to permit the wrapping material to be pressed thereagainst to sever the same after the wrapping of the article is completed.

In Figs. 15 and 16 we have shown a modified form of device wherein the shuttle comprises an annular casing constructed of any suitable material, and which may be of two sections, equal or otherwise, as preferred, and consist of an inner wall 69 and side walls 70, which are apertured to permit inspection of the contents. Said sections, as shown in the drawings, are hinged together by means of a bolt or pintle 71, engaging the lead section of each side wall together, but affording no obstruction to the interior of the shuttle. The folded wrapping material, which is designated by the reference numeral 72, is first laid into a carton or cartridge 73, constructed as shown of thin sheet metal, and the carton or cartridge containing said folded paper is then placed into the shuttle substantially as before described, and is firmly retained in place by detents 74, secured one in each shuttle section and adapted to protrude from the wall thereof to engage the cartridge. An outer wall 75, is provided on each of the shuttle sections, and coacts with said inner and side walls to form a pocket receiving the ends of the cartridge 73, for the paper thereinto. Each of the shuttle sections is, as in the construction previously described, provided with an end wall denoted respectively by the reference numerals 76 and 77, and at the extremity of each of said shuttle sections is an end or terminal wall 78 and 79, respectively, which abut one another when the shuttle is closed. Secured upon said respective walls 76 and 77, are strong leaf springs 80, which bear against the ends of the cartridge 73, holding the same toward the detents 74, which maintain the same associated with the shuttle sections. A spring pressed latch bolt 81, normally projects through registering apertures in the abutting end walls 78 and 79,

to lock said shuttle sections in closed relation, and a leaf spring 82, is engaged on the wall 79, and presses upon the tail of said latch bolt 81, to hold the same at all times in locking engagement. Apertures 83, are provided in the walls 75, of the shuttle sections to permit engagement therewith of mechanisms forming a part of the wrapping machine which act to swing the shuttle sections open about the pintle 71, and the insertion into said apertures of mechanism for the purpose causes the tail of the latch bolt 81, to be thrown upwardly against the stress of the spring, thereby unlatching the shuttle sections. As in the construction previously described the paper 72, is laid in arc shaped folds within the cartridge members, and the inner end of the strip is drawn outwardly through the inner wall 69, of one of the shuttle sections between rollers 84, on each side of a slot in said inner wall, and thence threaded through mechanism disposed within the compartment formed between the walls 77 and 79, of one of the shuttle sections, which act to fold the material longitudinally upon itself as the strip is drawn therethrough during the wrapping operation. This mechanism comprises a tension plate 85, and a folder nozzle 86, the paper being drawn first through the tension plate and then around and through the folder nozzle and then led to the article being wrapped which is indicated by the character Z. As before described, a reel 87, is mounted within the compartment afforded in the other shuttle section between the walls 76 and 78, upon which a coil of wire is wound and the wire, indicated by the reference numeral 88, is led therefrom around a suitable tension roller 89, and thence to the article being wrapped, being applied simultaneously with the paper wrapping.

The operation is as follows: The article to be wrapped is inserted into the machine resting upon the respective rollers 6 and 7, in upright position, the shuttle of course having been first opened to receive the article therein and then locked in closed position. The wrapping material X, is then drawn through the tension device and folder mechanism of the shuttle, as shown in Fig. 4, and applied to the article indicated by the letter Z in Fig. 4, and shown in dotted lines. The clutch member 12, on the drive shaft 10, is next engaged by shifting certain of the levers, whereby the shaft 10, is driven, thereby rotating the shuttle, due to the direct drive from the gear 20, and also driving the feed rollers 6 and 7, from the worm 13, on said shaft 10, which drives the shaft 15, so that the article to be wrapped is rotated at a relatively slow but uniform rate. Owing to the high speed of rotation of the shuttle the package of folded paper therein is thrown outwardly by centrifugal action, re-

lieving all pressure from the inner folds of the paper from which the strip is drawn, thus obviating any tendency to tear the paper. The paper passes around the tension roller 47, and thence through the folder before described where the paper is folded longitudinally, so that the outer edge of the spirally wrapped strip upon the article is of double thickness when applied. When the wrapping is completed the strip is severed upon the cutter 68, and the clutch 12, having been disengaged, the shuttle is opened by positioning the same with the respective abutment walls 31 and 32, thereof, disposed on the lower side and after unlatching the bolt 33, swinging the hinged sections upwardly.

The construction of the shuttle permits a maximum quantity of wrapping material to be contained therein to enable a large number of objects to be wrapped without refilling the shuttle, and furthermore, inasmuch as the wrapping material is withdrawn from the inner folds of the folded material no resistance to withdrawal is exerted, due to the weight of the paper in the shuttle. The paper is inserted into the shuttle already folded by retracting the bolt 40, whereby the hinged sections 36 and 37, are unlocked, and folding said hinged sections outwardly away from one another, affording an unobstructed access to the interior of the shuttle. The wire bobbin may, of course, be removed when not required. When required, the wire is passed around the object and wound over the paper, both being applied simultaneously. When the shuttle is opened, the plate 50, within the shuttle, which is secured to the inner wall of one of the sections, is drawn along the inner wall of the other section to bridge the gap between the shuttle sections and to support the inner layers of the wrapping material away from the gap, so that the same cannot be pinched therein when the shuttle is again closed.

We have shown preferred forms of a shuttle capable of operating at high speed and we have referred in the specification to the wrapping of annular bodies. It is obvious, however, that numerous variations and modifications in the construction of the shuttle may be made without departing from the principles of this invention, and that the machine using such a shuttle is adaptable to wrapping bodies of any kind that may be passed through the eye of the shuttle, as, for example, a rod, bar or tube, and many other objects. We therefore do not purpose limiting the patent granted otherwise than necessitated by the prior art.

We claim as our invention:

1. In a wrapping machine an annular shuttle having a compartment therein to receive folded wrapping material, and a ten-

sion device for said material on the inner side of the shuttle.

2. In a wrapping machine a chambered, rotatable shuttle having wrapping material therein in concentric folds, a folding nozzle through which the wrapping material is drawn from the inner side the folded package of wrapping material and acting to fold the wrapping material longitudinally and direct it spirally around the material wrapped.

3. In a wrapping machine a rotatable annular shuttle having concentrically folded wrapping material therein discharging through the inner periphery, the shuttle thereby utilizing centrifugal force to obviate internal resistance to the feed of the wrapping material.

4. In a machine of the class described, a rotatable hollow, annular shuttle carrying folded wrapping material therein, having layers thereon arranged concentric with the axis of the shuttle.

5. In a machine of the class described, a rotatable shuttle comprising hingedly connected segments adapted to be opened to receive the article to be wrapped through the eye thereof and affording when closed a chamber to receive a package of folded wrapping material, means locking the shuttle closed, an eduction aperture for the wrapping material, and means for folding the edge of the wrapping material longitudinally during wrapping.

6. In a machine of the class described, a rotatable hollow shuttle affording an interior chamber for a package of folded wrapping material having layers arranged concentric with the axis of the shuttle, and a tension and folding device supported on and by said shuttle through which the wrapping material is drawn in wrapping, said shuttle having an aperture in the inner periphery thereof through which the wrapping material is drawn from the inner side of the package.

7. In a machine of the class described, an annular rotatable shuttle comprising hingedly connected segments adapted to be opened to receive the article to be wrapped through the eye thereof and affording when closed an unobstructed chamber to receive a package of folded wrapping material, means locking the shuttle closed, a removable wall on the shuttle for insertion of wrapping material, an eduction aperture for the wrapping material in the inner wall of the shuttle, and means for folding the wrapping material longitudinally during wrapping.

8. In a wrapping machine a rotatable shuttle adapted to contain wrapping material laid in a series of arc shaped folds.

9. In a device of the class described, an annular rotatable shuttle, a chamber there-

in shaped to receive concentric folds of wrapping material and retain the same in such form and having an aperture to permit the withdrawal of said material, and a tension and folding device mounted on the shuttle substantially opposite to said aperture.

10. In a wrapping machine of the class described, a shuttle comprising hingedly connected sections adapted to receive folded wrapping material therein.

11. In a device of the class described, a shuttle comprising hingedly connected sections adapted to receive concentric layers of folded wrapping material, locking means for said shuttle sections, and a plurality of mechanisms on said shuttle for applying said material to an article to be wrapped.

12. In a device of the class described, a shuttle comprising hingedly connected sections having a compartment extending from one section to the other for containing concentric layers of folded wrapping material, each of said sections also provided with a smaller compartment, and mechanisms within each of said smaller compartments for applying the wrapping material to an article being wrapped.

13. In a device of the class described, a rotatable shuttle adapted to carry wrapping material loosely therein, means on said shuttle to support the wrapping material against centrifugal force, and an outlet on the inner side of the shuttle to permit withdrawal of the wrapping material there-through.

14. In a device of the class described, a rotatable shuttle adapted to carry wrapping material loosely folded in layers, means on said shuttle to support said wrapping material as the same is held outwardly by centrifugal force when the shuttle rotates, and a feed mechanism to permit passage of the wrapping material to an article being wrapped, said shuttle provided with an opening in the inner peripheral wall thereof through which said material is fed from the inner layer.

15. In a device of the class described, a rotatable shuttle adapted to carry layers of loosely folded wrapping material, a feeding outlet on the inner side of the shuttle to permit withdrawal of the wrapping material from the innermost layer, and means on said shuttle to permit the wrapping material to be pressed thereagainst to sever the same from an article which has been wrapped.

16. In a device of the class described, a sectional shuttle adapted to rotate, carrying layers of loosely folded wrapping material held in position by centrifugal force with the weight of said wrapping material on the outermost layer thereof, mechanism associated with said shuttle to permit withdrawal of said material from the innermost

- layer, and means pivoted on one of the shuttle sections adapted to engage the other of said sections to lock the same together.
17. In a device of the class described a hollow annular shuttle comprising segments separable to permit said shuttle engaging through the eye of an annular body, a section in a wall of the shuttle adapted to be opened to admit insertion into the shuttle of a package of wrapping material, and a bridge member engaged in one of said segments and slidale in the other to support the wrapping material at the gap between the sections when the shuttle is open.
18. In a device of the class described a hollow annular shuttle comprising segments separable to permit said shuttle engaging through the eye of an annular body, a part of one wall of the shuttle being removable to admit insertion into the shuttle of a package of wrapping material, and a bridge member engaged on one of said segments and slidale in the other to support the wrapping material at the gap between the sections when the shuttle is open and means holding said removable wall section closed normally.
19. In a machine of the class described an annular shuttle comprising a plurality of sections hingedly connected, a compartment in one or more of said sections for wrapping material adapted to be loosely contained therein, and a bridge acting to support the wrapping material when the shuttle is opened.
20. In a machine of the class described, an annular shuttle comprising a plurality of hingedly connected sections having a compartment in one or more of said sections adapted to receive folded wrapping material loosely therein, a bridge adapted to support the wrapping material at the gap when the shuttle is opened, and a spring pressed bolt secured in one of said sections adapted to engage the other of said sections to lock the shuttle when closed.
21. In a machine of the class described an annular shuttle comprising a plurality of hingedly connected sections, removable outer peripheral walls for the shuttle affording an elongated compartment therein for the wrapping material loosely contained therein, mechanism to open the shuttle to release therefrom the article wrapped, and a support in said shuttle for the wrapping material when the shuttle is opened. 50
22. In a wrapping machine, a sectional hingedly connected shuttle, means for carrying wrapping material in concentric arc-shaped folds therein, and means permitting the shuttle to be opened and closed without removal of said wrapping material. 60
23. In a device of the class described, a shuttle for carrying and feeding folded wrapping paper to an article being wrapped, tensioning mechanism adjustably mounted upon said shuttle for the paper fed from the shuttle, and folding means pivoted on said shuttle to fold the tensioned portion of the paper. 65
24. In a device of the class described, hollow rotatable means carrying wrapping material folded therein to apply the same upon an article, and a tension mechanism for tensioning the wrapping material as it leaves 70 said rotatable means. 75
25. In a wrapping machine, means carrying paper in arc-shaped folds and acting to apply the paper to an article, a tension mechanism for tensioning the paper feeding 80 to the article, and folding means to turn the edge of the tensioned portion of the paper.
- In testimony whereof we have hereunto subscribed our names in the presence of two 85 subscribing witnesses.
